US00D952881S

(12) **United States Design Patent** (10) **Patent No.:** **US D952,881 S**
(45) **Date of Patent:** **** May 24, 2022**

(54) **HAND MASSAGER**

(71) Applicant: **Xiamen Emoka Health Science & Technology Co., Ltd.**, Fujian (CN)

(72) Inventor: **Guanghua Zhou**, Fujian (CN)

(73) Assignee: **Xiamen Emoka Health Science & Technology Co., Ltd.**, Fujian (CN)

(**) Term: **15 Years**

(21) Appl. No.: **29/716,029**

(22) Filed: **Dec. 5, 2019**

(51) LOC (13) Cl. **28-03**

(52) U.S. Cl.

USPC **D24/215**
